PRINTING TELEGRAPH MANUAL EXCHANGE
SYSTEM

Eric Malcolm Swift McWhirter and James George Flint, Aldwych, London, England, assignors to Western Electric Company, Incorporated, New York, N. Y., a corporation of New York

Application October 25, 1930, Serial No. 491,114
In Great Britain November 6, 1929

18 Claims. (Cl. 178—4.1)

This invention relates to an exchange system for the interconnection of subscriber telegraph apparatus.

According to one feature of the invention the signals for setting up the connection and for the telegraph message after the connection has been set up are sent from a substation over the same circuit.

According to another feature of the invention each substation is connected to the exchange by two wires only which form a complete metallic circuit for the signals for setting up the connection and for telegraphic communication to and from the substation.

According to still another feature of the invention the operators at the exchange are provided with printing telegraph apparatus and each cord circuit contains means for connecting thereto this apparatus so that any communications between subscriber and operator are carried out solely by means of type printing telegraph apparatus.

According to yet another feature of the invention the apparatus at a called station is automatically set in operation to receive a communication on the completion of a connection thereto.

The invention also provides a novel junction circuit which comprises two junction lines only and relays at each end of the junction line connected to repeat telegraph signals in the respective directions and so arranged as to remain unaffected by messages in the opposite direction.

One embodiment of the invention will now be described in connection with the accompanying drawing in which:

Fig. 1 represents the apparatus at a subscriber's station and the apparatus associated with his line at the exchange;

Fig. 2 shows an operator's cord circuit;

Fig. 3 shows a junction circuit for the interconnection of two telegraphic exchanges; and

Fig. 4 shows a cord circuit by means of which any subscriber may be connected to a plurality of other subscribers.

A type printing telegraph apparatus located at a subscriber's station comprises transmitter contacts TC, which when operated by a keyboard or automatic transmitter will open and close a line circuit in accordance with the signals which are to be sent. These contacts are normally closed. The apparatus also comprises printing mechanism controlled by a relay PM responding to the received impulses and a motor TM which drives the mechanism both for printing and transmitting purposes. A relay RM of the slow-release

type is connected in series with the transmitter contacts and relay PM. The motor is adapted to be connected to the lines P1, P2 of a local source of electric lighting or power supply over the normally open contacts of the relay RM. Contacts TMC are arranged to be closed whenever the motor is running. The subscribers' lines L1, L2, leading to the exchange are closed at the substation through the slow-release relay RM, receiving relay PM, the normally closed transmitter contacts TC, a condenser K, and a pair of polarized relays PR1 and PR2. The polarized relays are arranged to operate simultaneously on a battery reversal through the condenser K and will remain in the position to which they were last operated.

In order to initiate a call, the subscriber momentarily depresses a non-locking key CK which closes the circuit of the motor TM which immediately closes its contacts TMC. A calling relay CR at the exchange and the relay RM thereupon operate in a circuit from the positive pole of battery U, contacts of jack CJ, line L1, relay RM, relay PM, contacts TC, normally closed contacts of relay PR1, key RK, contacts TMC, line L2, contacts of jack AJ, relay CR, contacts of jack CJ, negative pole of battery. Relay CR operates, lights a calling lamp CL and a pilot lamp PL and rings an alarm bell AB.

The operator inserts her answering plug AP into the jack AJ and throws the key CCK to the left. This connects her type printing telegraph apparatus OM in series with that at the subscriber's station and with the battery U, the circuit being as follows: positive pole of battery U, contacts of jack CJ, line L1, relay RM, relay PM, contacts TC, contacts of relay PR1, key RK, contacts TMC, line L2, ring spring of jack AJ, ring of plug AP, contacts of key CCK, operator's machine OM, back contact of relay CSR, contacts of key CCK, tip of plug AP, tip spring of jack AJ, and negative terminal of battery U. The operator then by typing asks the subscriber for the wanted number which is thereupon typed back to her.

Local call

Assume first that the wanted subscriber is on the same exchange. The operator inserts a plug CP of the cord circuit into the jack CJ belonging to the wanted subscriber. The sleeve of the jack CJ is grounded which serves a purpose to be mentioned later and also operates the relay CSR. The battery connected to the springs of the jack CJ of the called subscriber is discon-

5 nected and all battery supply is then derived from the battery U connected to the line L1 of the calling subscriber. The condenser K of the called subscriber is charged by the battery U
 10 5 of the calling subscriber; the connection being as follows: positive battery U of calling subscriber's line L1, calling subscriber's set, line L2, ring of jack AJ and of plug AP, key CCK, contacts of relay CSR, ring of plug CP and of called subscriber's jack CJ, line L2; through the called subscriber's set which includes condenser K, line L1, tip of jack CJ and of plug CP, contacts of relay CSR, tip of plug AP and of calling subscriber's jack AJ, and negative battery U. Batteries U are preferably separate batteries and they
 15 may have in series the usual current limiting resistances. The operator then throws the key CCK to the right and thereby reverses the connections between the tips and rings of the plugs AP and CP. The key CCK in this position connects the tip of plug AP to the ring of plug CP, and the ring of plug AP to the tip of plug CP. A charging current of short duration flows from battery U of the calling subscriber to condenser K of the called subscriber, the charge on the condenser K being opposite in polarity to that impressed upon the condenser in the circuit previously traced just before the key CCK was thrown to the right. The charging current is
 20 sufficient to operate the relays PR1 and PR2 of the called subscriber's set. Relay PR2 closes the circuit of the subscriber's motor which commences to rotate. Relays PR1 and PR2 together with the condenser K typify means which operate as a result of current reversals to start the subscriber's motor or perform an equivalent function and then remove themselves from operative relation to the line so that their impedance is no longer effective in the line. The operator
 25 then restores the key CCK to normal and relays PR1 and PR2 restore. The sequence of events of inserting the plug CP into jack CJ, operating key CCK to the right and then restoring it is performed in moderately rapid sequence, i. e.
 30 35 within two or three seconds. The relay RM operates and closes its contacts, thus keeping the motor running.

40 The connection between calling and called subscribers is thus complete and communication may take place. A message may be sent by the calling subscriber and received on the called subscriber's instrument in the absence of any operator at the substation.

45 The operator at the exchange may connect her own machine OM in series in the circuit by moving the key CCK to the left, the circuit then being positive pole of battery U, contacts of jack CJ, line L1, calling subscriber's apparatus, line L2, ring spring of jack AJ, ring of plug AP, contacts 50 of key CCK, operator's machine OM, contacts of key CCK, operated contacts of relay CSR, ring of plug CP, called subscriber's apparatus, tip of plug CP, contacts of key CCK, operated contacts of CSR, (two sets), contacts of key CCK, tip of plug AP, tip spring of jack AJ, contacts of jack CJ, negative battery. Thus the operator is able to satisfy herself that a satisfactory connection has been completed.

55 60 When the key CCK is restored to normal, relay SR is included in the line circuit between the two subscribers. This relay is made slow to release so that the normal telegraph impulses do not cause it to de-energize.

65 The release of the connection is under control 70 of the calling subscriber and in order to release

he presses the key RK. This key breaks the short circuit which had been maintained round the relays PR1 and PR2 and condenser K and causes the relays RM at each station to de-energize. This key RK is held down until the contacts of relay RM open after a predetermined time and so stop the motor whereby the contacts TMC open. It may then be assumed that the motor at the called station has also stopped. The opening of the line circuit causes the de-energization of the relay SR at the exchange and this closes the circuit of the thermostat relay THR, which operates after a delay which is sufficient to ensure that the motors at the calling and called stations have stopped and the supervisory lamp 15 SL is lighted. This signals to the operator that the plugs may be removed from the jacks.

10 If the calling subscriber should require a connection to a subscriber on another exchange the operator inserts the plug CP into the jack OJ 20 belonging to the junction circuit shown in Fig. 3. Two telegraph relays are provided at each end of a junction circuit. Relays A and C have each two windings denoted by A1 and A2 and C1 and C2, respectively. These relays are polarized and 25 their armatures are biased toward the spacing contacts. The relays B and D are telegraph receiving relays. Normally, when the junction circuit is idle, relay A is operated in a circuit extending from the negative terminal of the local 30 battery G over the operating winding A1, back contact of relay B, back contact of relay M, back contacts of relay R, another back contact of relay M, resistance and positive battery G. Relay C is operated in a similar circuit from battery 35 H. The junction lines JL1 and JL2 are normally connected in series over the windings of B and D, the holding windings A2 and C2 and marking contacts of relays A and C.

40 When the operator inserts the calling plug CP into the jack OJ, relay M operates to ground over the spring of the jack OJ and disconnects the above circuit for winding A1, but at its upper front contact relay M switches the battery U (Fig. 1) through to relay A to maintain the winding A1 of the latter in a circuit from negative battery U (Fig. 1) upper spring of jack CJ, tip of jack AJ, tip of plug AP, uppermost left made contact of key CCK, resistance, front contact of relay CSR, uppermost right contact of key CCK, 45 tip of plug CP, tip of jack OJ, upper front contact of relay M, winding A1, back contact of relay B, ring of jack OJ, ring of plug CP, inner right made contact of key CCK, front contact of relay CSR, inner left made contact of key CCK, ring 50 of plug AP, ring of jack AJ, line L2 to line L1, ring of jack CJ to positive battery U.

55 Upon the key CCK (Fig. 2) being thrown to the right the current in the winding A1 is reversed and causes the armature of relay A to move over to its spacing contact. The armature in this position closes the circuit through the operating winding of relay D at the other end of the junction line in series with the holding winding C2 of relay C and battery S at the outgoing end of the junction line. The complete circuit extends from the negative terminal of battery S, through armatures of relays E and A, junction line JL1, armature of relay C, winding C2 of relay C, winding of relay D, and line JL2 to 70 positive terminal of S. The current in the holding winding C2 of relay C aids that in the operating winding and keeps the armature on its marking contact when the relay D is operated. During the time of movement of the armature of relay D, 75

the winding C_1 is disconnected but a current in the winding C_2 prevents any operation of the associated armature. Relay F is then energized in series with the winding C_1 and operates a relay 5 CR to light the calling lamp. The operator at the second exchange inserts her plug AP into the jack IJ at the other end of the junction circuit and this causes the operation of relays Q and N to local contacts on the jack, Q being slightly 10 slower to operate than N. Relay N disconnects the winding C_1 from the local circuit and reconnects it in the following circuit: tip spring of jack IJ on the right of the figure, lower contact of relay Q, battery EB, upper contact of 15 relay Q "make" contact of relay N, winding C_1 , "break" contact of relay D, back to the ring spring of the jack IJ. This circuit is at the moment open at the relay D, but as soon as the operator at the first exchange restores the key 20 CCK to normal, relay A operates to its marking contact and the windings C_2 and D are de-energized. The armature of relay D is released. During the movement of relay D there is a short time when both windings C_1 and C_2 are de-energized, but relay F is made slightly slow to release so that any movement of relay C will be without effect at the left-hand end of the junction circuit. As soon as relay D has released, the winding C_1 is energized in the circuit previously 25 traced. When relay N operates, the circuits for relays F and CR are broken and the calling lamp extinguished. The operator at the second exchange can now type to the operator at the first exchange, transmission from the second to the 30 first exchange being relayed by relays C and B and transmission from the first exchange to the second exchange being relayed by relays A and D. The calling subscriber is in series in the circuit with the machine of the operator at the first 35 exchange and so can follow the progress of the call.

The operator at the second exchange upon ascertaining the requirements of the call inserts her plug CP into the jack of the wanted subscriber. The connections and operation are similar to a local call on this exchange except that the telegraph relays C and D take the place of the calling subscriber's machine in the circuit and the necessary signaling current is supplied by the battery EB instead of by the battery U in Fig. 1. When the keys CCK of both operators cord circuits are restored to normal the two subscribers are in communication, but either operator can monitor on the circuit so long as 40 her key CCK is kept to the left.

The release of the connection takes place in a manner similar to that on a local call, the relays THR in each cord circuit operating to light their respective supervisory lamps.

45 If a subscriber wishes to send a message simultaneously to a plurality of other subscribers, the apparatus shown in Fig. 4 is utilized. The subscriber originates the call in the normal manner and the operator plugs into jack AJ (Fig. 1) 50 with a plug AP (Fig. 2) in the usual way. When the requirements of a subscriber have been ascertained, the operator inserts the plug CP into the jack BJ₁ in Fig. 4 which connects the tip and ring of the plug CP to a telegraph relay TR. 55 The tongue and marking contacts of this relay are connected through a battery and resistance to the tip and ring springs of a second jack BJ₂ into which the operator can insert a plug APB. The plugs CP₁ to CP₄ are inserted into the calling jacks of the required subscribers or into the 60

jacks of junction circuits if the subscribers are on another exchange. Sleeve relays SR₁ to SR₄ complete the circuits to these plugs only when they have been inserted into a jack. Pressure of the key BCK reverses the connections to all the 5 subscribers' lines and thus starts the motors at all the called stations into operation. The calling subscriber can then transmit to all the called subscribers' circuits in parallel.

In many cases it will be necessary in order to 10 ensure satisfactory transmission that the batteries U, EB, etc., providing the signaling current should be of a voltage considerably in excess of that used for telephone exchange working and it will be observed that in all cases the sleeves of 15 the jacks, contacts of which are connected to these signaling batteries are grounded, so that the sleeve of the plug is also grounded and the operator effectively protected against shocks.

What is claimed is:

1. In a motor controlling arrangement, a motor, a line connected to a distant source of current, means including a source of power and a circuit changing device responsive to a flow of current in said line for starting said motor, a condenser 20 for obstructing current in said line, and remote control means for short-circuiting said condenser.

2. A motor control arrangement comprising 30 a relay adapted to control a motor circuit, a line connecting said relay to a distant source of current, a condenser and a polarized relay in said line whereby current in the line is obstructed, remote control means for operating said polarized relay, said means comprising a device for reversing the polarity of the distant current source, means responsive to the operation of the polarized relay for starting the motor, and means responsive to the starting of the motor for short-circuiting said polarized relay and condenser. 40

3. In a printing telegraph system, a telegraph set comprising a transmitter, a receiver and a motor, a line circuit including said transmitter and receiver in series, a condenser in said series circuit for obstructing current therein when the 45 set is not in use, and means controlled by said motor for automatically short-circuiting said condenser during operation of said motor.

4. In a printing telegraph system, a telegraph set comprising a receiving instrument and a 50 motor, a line circuit including said receiving instrument, and means for starting said motor by remote control, said means comprising a polarized relay and a condenser serially connected in said line circuit, said polarized relay being adapted 55 to close a pair of contacts for the motor circuit upon the receipt from the line of two current impulses of opposite polarity.

5. In a telegraph system, a plurality of subscribers' stations each connected to a loop circuit and equipped with a telegraph set for sending and receiving telegraph messages over said loop circuit, means for applying a direct current source to said loop circuit, switching means at each of the subscribers' stations for switching in 60 and out the subscribers' telegraph set to be controlled by a current flow from said direct current source, and a condenser in series with said switching means for preventing a permanent current flow during the time in which the station is 65 not in use.

6. In a telegraph system, a plurality of subscribers' stations each connected to a loop circuit and equipped with a telegraph set for sending and receiving telegraph messages over said loop 75

circuit, means for applying a direct current source to said loop circuit, switching means at each of the subscribers' stations for switching in and out the subscribers' telegraph set to be controlled by a current flow from said direct current source, a condenser in series with said switching means for preventing a permanent current flow during the time in which the station is not in use, and other switching means at each of the subscribers' stations for short-circuiting the condenser when the station is to be used.

7. In a telegraph system, a plurality of subscribers' stations each connected to a loop circuit and equipped with a telegraph set for sending and receiving telegraph messages over said loop circuit, means for applying a direct current source to said loop circuit, switching means at each of the subscribers' stations for switching in and out the subscribers' telegraph set to be controlled by a current flow from said direct current source, a condenser in series with said switching means for preventing a permanent current flow during the time in which the station is not in use, and other switching means at each of the subscribers' stations for short-circuiting the condenser when the station is to be used, said other switching means being controlled by a device which is operated only when the telegraph set is ready for use.

8. In a telegraph system, a plurality of subscribers' stations each connected to a loop circuit and equipped with a telegraph set for sending and receiving telegraph messages over said loop circuit, means for applying a direct current source to said loop circuit, switching means at each of the subscribers' stations for switching in and out the subscribers' telegraph set to be controlled by a current flow from said direct current source, a condenser in series with said switching means for preventing a permanent current flow during the time in which the station is not in use, and other switching means at each of the subscribers' stations for short-circuiting the condenser when the station is to be used, said other switching means being controlled by a device which is supplied from the power source of the telegraph set.

9. In a telegraph exchange system, an exchange, a plurality of subscribers' stations each connected to said exchange over a loop circuit and equipped with a telegraph set for sending and receiving telegraph messages over said loop circuit, means at the exchange for applying a direct current source to said loop circuit, switching means at each of the subscribers' stations for switching in and out the subscribers' telegraph set to be controlled by a current flow from said direct current source, and a condenser in series with said switching means for preventing a permanent current flow during the time in which the station is not in use.

10. In a telegraph exchange system, an exchange, a plurality of subscribers' stations each connected to said exchange over a loop circuit and equipped with a telegraph set for sending and receiving telegraph messages over said loop circuit, means at the exchange for applying a direct current source to said loop circuit, switching means at each of the subscribers' stations for switching in and out the subscribers' telegraph set to be controlled by a current flow from said direct current source, a condenser in series with said switching means for preventing a permanent current flow during the time in which the station is not in use, and other switching means at each

of the subscribers' stations for short-circuiting said condenser when the station is to be used.

11. In a telegraph exchange system, an exchange, a plurality of subscribers' stations each connected to said exchange over a loop circuit and equipped with a telegraph set for sending and receiving telegraph messages over said loop circuit, means at the exchange for applying a direct current source to said loop circuit, switching means at each of the subscribers' stations for switching in and out the subscribers' telegraph set to be controlled by a current flow from said direct current source, a condenser in series with said switching means for preventing a permanent current flow during the time in which the station is not in use, and other switching means at each of the subscribers' stations for short-circuiting said condenser when the station is to be used, said other switching means being controlled by a device which is operated only when the telegraph set is ready for use.

12. In a telegraph exchange system, an exchange, a plurality of subscribers' stations each connected to said exchange over a loop circuit and equipped with a telegraph set for sending and receiving telegraph messages over said loop circuit, means at the exchange for applying a direct current source to said loop circuit, switching means at each of the subscribers' stations for switching in and out the subscribers' telegraph set to be controlled by a current flow from said direct current source, a condenser in series with said switching means for preventing a permanent current flow during the time in which the station is not in use, and other switching means at each of the subscribers' stations for short-circuiting said condenser when the station is to be used, said other switching means being controlled by a device which is supplied from the power source of the telegraph set.

13. In a telegraph exchange system, an exchange, a plurality of subscribers' stations each connected to said exchange over a loop circuit and equipped with a telegraph set for sending and receiving telegraph messages over said loop circuit, means at the exchange for applying opposite direct current potentials to said loop circuit, polarized switching means at each of the subscribers' stations for switching in and out the subscribers' telegraph set which are controlled by said direct current potentials, and a condenser in series with said polarized switching means.

14. A printing telegraph subscriber's station which comprises a printing mechanism, a motor for driving said mechanism, motor control means for controlling said motor, a printing magnet for controlling said printing mechanism, a centrifugally operated contact associated with said driving motor, and a circuit including said printer magnet and centrifugally operated contacts extending to a central office.

15. A printing telegraph subscriber's station comprising a motor driven telegraph printer, a printer magnet associated therewith, a loop circuit including said printer magnet which extends to a central office, and centrifugal means associated with said motor for maintaining said loop circuit closed as long as said motor is rotating.

16. In a telegraph system, a plurality of subscribers' stations each connected to a loop circuit and equipped with a telegraph set for sending and receiving telegraph messages over said loop circuit, a central office through which said loop circuits, may be interconnected, means for applying a direct current source at said central office

to said loop circuit, switching means at each of the subscribers' stations for switching in and out the subscribers' telegraph set to be controlled by a current flow from said direct current source, 5 a condenser in series with said switching means for preventing a permanent current flow over said loop circuit during the time in which the station is not in use, and other switching means at each of the subscribers' stations for removing the condenser from series relation to the loop circuits 10 when the station is to be used.

17. A printing telegraph exchange system comprising a first station, a second station, a line normally open to continuous direct current connecting said stations, a relay connected in said line at said second station responsive to potential reversals applied to said line at said first station for closing said line to direct current, and 15

additional means whereby the potential reversals applied to said line close the operating circuit for the motor of a printing telegraph instrument located at said second station.

18. A printing telegraph exchange system comprising a first station, a second station, a line normally open to continuous direct current connecting said stations, a relay connected in said line at said second station responsive to potential reversals applied to said line at said first station 5 for closing said line to direct current, and additional apparatus whereby the potential reversals applied to said line start the motor of a printing telegraph instrument located at said second station and also disconnect said relay from operative 10 relation to said line.

ERIC MALCOLM SWIFT McWHIRTER.
JAMES GEORGE FLINT.
